UNITED STATES PATENT OFFICE

FERDINAND B. HERZ, OF DETROIT, MICHIGAN, ASSIGNOR TO LONG MANUFACTURING COMPANY, OF DETROIT, MICHIGAN, A CORPORATION OF MICHIGAN

RADIATOR UNIT

Application filed March 13, 1930. Serial No. 435,589.

This invention relates to radiator units of the type commonly used upon motor vehicles now commercially produced and has particular reference to an improved auxiliary front for the unit.

One of the objects of this invention is to provide an auxiliary front adapted to assume a position within the radiator shell in advance of the core and comprising a plurality of substantially vertical ribs extending across the entire front opening in the shell to resemble the conventional vertical shutter unit when fully opened. Moreover, by virtue of the fact that the ribs aforesaid extend lengthwise across the shell, the appearance of the radiator unit is greatly enhanced since it gives the unit the appearance of being relatively long and comparatively narrow.

Another object of this invention is to provide a radiator unit having an auxiliary front so designed as to offer the minimum amount of resistance to the passage of air irrespective of wind direction and at the same time to substantially conceal the radiator core and completely conceal the usual tanks or headers and the space between the core and the tapering side walls of the shell. Thus it will be observed that the auxiliary front permits the installation of tanks of greater capacity without exposing the same and also permits the elimination of all dead core material necessary in the conventional design of radiators due to the decided upward taper of the side walls of the radiator shell.

A further object of this invention is to provide improved means for securing the auxiliary front in position so that the latter function to reinforce the radiator shell.

With the foregoing as well as other objects in view, the invention resides in the construction of the radiator unit including the auxiliary front which will be made more apparent as this description proceeds, especially when considered in connection with the accompanying drawings, wherein:

Figure 1 is a front elevational view of a radiator unit with certain parts broken away for the sake of clearness.

Figure 2 is a sectional view taken on the line 2-2 of Figure 1.

Figure 3 is a cross-sectional view taken on the line 3-3 of Figure 1.

Figure 4 is a view similar to Figure 2 showing a modified form of construction.

Referring now to the drawings, it will be noted that there is illustrated in Figure 1 a radiator unit 10 comprising a shell 11 transversely curved as indicated at 12 and having a vertically elongated opening 13 therein exposing a heat exchange unit 14. The heat exchange unit is preferably of conventional design and comprises a core arranged within the boundaries of the shell 15 and having upper and lower water headers 15 and 16, respectively, communicating with each other by means of a series of tubes 17 having fins 18 secured thereto in accordance with the usual practice.

The shell 11, in addition to being transversely curved, as stated above, tapers upwardly as shown in Figure 1 and the front panels 19 are relatively small in size. With a radiator shell of the type outlined above, considerable difficulty is experienced in fitting a radiator core into the shell in such a manner that the same will present a neat and pleasing appearance since it is impractical to transversely curve the front face of the core and to taper the same to correspond to the shell. Moreover, by reason of the relatively small front panels 19 of the shell it is substantially impossible to so position the core within the shell as to prevent the headers associated with the radiator core from being visible through the front of the shell since the headers must bear a definite relation to the size of the radiator core. As a consequence, some provision must be made to not only conceal the headers and the space between the opposite sides of the core and adjacent walls of the shell caused by tapering the latter, but also to compensate for the space between the inner surfaces of the front panels 19 and the core. The above has heretofore been accomplished by forming what is commonly known as dead core material upon the heat exchange unit, but this method is extremely objectionable owing

to not only conceal the headers and the space between the opposite sides of the core and adjacent walls of the shell caused by tapering the latter, but also to compensate for the space between the inner surfaces of the front panels 19 and the core. The above has heretofore been accomplished by forming what is commonly known as dead core material upon the heat exchange unit, but this method is extremely objectionable owing

ing to the expense involved in manufacture.

- The present invention contemplates eliminating the above difficulties by providing an auxiliary front 20 disposed within the space between the radiator core and shell and conforming to the shape of the latter. The auxiliary front 20 is fashioned to simulate a shutter unit when opened and comprises a body portion 21 formed of a single sheet of metal and capable of being bent to substantially any desired shape. The body portion comprises a plurality of vertically extending ribs 22 extending lengthwise across the opening in the shell and being fashioned to offer the minimum resistance to the passage of air through the openings 23 intermediate the ribs and to simulate the blades of a conventional shutter when in open position. The vertical ribs 22 of the auxiliary front are maintained in proper spaced relation to each other and are connected together at the upper and lower ends by means of the web portions 24 and 25, respectively. The web portions 24 and 25 are formed integral with the ribs and project into the opening in the shell a sufficient distance to completely conceal the upper and lower headers 15 and 16. The space formed by tapering the shell between the lower side portions of the core and adjacent walls of the shell are concealed by the web portions 26 forming a continuation of the web portions 25 and extending longitudinally of the ribs.
- For reinforcing the auxiliary front to maintain the same in the desired shape and at the same time for supporting the auxiliary front in engagement with the shell, I provide cross members 27 having the front surface 28 thereof corresponding to the desired transverse curvature of the shell and secured to the rear surfaces of the web portions 24 and 25 so as to be concealed thereby. The cross members 27 are formed adjacent the ends thereof with suitable spring fingers 29 adapted to be slightly compressed against the front face of the shell to urge the marginal portions of the auxiliary front into engagement with the rear surfaces of the front panels 19 of the shell. With the above arrangement the auxiliary front may be readily assembled and removed from the radiator unit and at the same time is securely held in place.
- In Figure 4 of the drawings I have shown a slightly modified form of construction differing only from the one hereinbefore set forth in the means for securing the auxiliary front in position within the shell. As shown in Figure 4, I provide suitable strips 30 having the rear ends thereof secured to the rear end portions of the shell as at 31 and having portions intermediate the ends offset inwardly and embracing opposite sides 65 of the radiator core as at 32. The inter-

mediate portions 32 of the strip project forwardly from the radiator core and are secured to the cross members 27 as at 33. The above construction is such that the strip forms a reinforcement for the side walls of the radiator shell in addition to securing the auxiliary front in position relative to the shell.

What I claim as my invention is:

1. The combination with a radiator unit having a shell and a core spaced rearwardly from the shell, of an auxiliary front within the shell simulating a shutter unit and substantially concealing said core. 75
2. The combination with a radiator unit comprising a shell and a core positioned in rear of the shell and having upper and lower headers normally visible through the opening in the shell, of an auxiliary front disposed within said shell in advance of the core, said auxiliary front having portions providing for the passage of air therethrough and simulating a shutter unit and having other portions completely concealing said headers. 80
3. The combination with a radiator unit having a core and a shell forming a housing for the core and having an open front permitting a circulation of air through the shell, of an auxiliary front having a body portion formed of a single piece of sheet metal arranged within the shell in advance of the core for substantially concealing the latter. 85
4. The combination with a radiator unit comprising a core and a shell forming a housing for the core and having an open front permitting the circulation of air through the shell, of an auxiliary front positioned within the shell in advance of the core and comprising a series of spaced ribs extending across the opening simulating a shutter unit, and means for supporting the auxiliary front within the shell. 90
5. The combination with a radiator unit comprising a core and a shell forming a housing for the core and having an open front permitting the circulation of air through the shell, of an auxiliary front positioned within the shell in advance of the core and apertured to permit the passage of air therethrough, and a cross member secured to the rear surface of the auxiliary front for reinforcing the same and having spring fingers engaging the core for holding said auxiliary front in position within the shell. 95
6. The combination with a radiator unit comprising a core and a shell forming a housing for the core and having an open front permitting the circulation of air through the shell, of an auxiliary front positioned within the shell in advance of the core and comprising a series of spaced ribs extending across the opening simulating a 100

- shutter unit, said auxiliary front having web portions connecting the ribs at the upper ends thereof and extending within the opening in said shell for completely concealing a portion of said core. 10
7. The combination with a radiator unit comprising a core having upper and lower headers and a shell forming a housing for the core and having an open front permitting the circulation of air through the shell, of an auxiliary front positioned within the shell in advance of the core and comprising a series of spaced ribs extending across the opening simulating a shutter unit, said auxiliary front having web portions formed integral with and connecting the ribs at the upper and lower ends thereof and extending within the opening in said front for completely concealing said headers. 15
8. The combination with a radiator unit comprising a core having upper and lower headers and a shell forming a housing for the core and having an open front permitting the circulation of air through the shell, of an auxiliary front positioned within the shell in advance of the core and comprising a series of spaced ribs extending across the opening simulating a shutter unit, said auxiliary front having web portions formed integral with and connecting the ribs at the upper and lower ends thereof and extending within the opening in said front for completely concealing said headers, and means for positioning said auxiliary front within the shell including members secured to the inner surfaces of the webs and operable to reinforce the auxiliary front. 20
9. The combination with a radiator unit comprising a core and a shell housing the core having side walls inclined relative to the adjacent side walls of the core, of an auxiliary front interposed between the core and shell and simulating a shutter unit, said auxiliary front having portions fashioned to permit the passage of air therethrough and having other portions concealing the space between the side walls of the shell and adjacent wall of the core. 25
10. The combination with a radiator unit comprising a core having upper and lower headers and a shell housing the core, of an auxiliary front substantially of one piece construction and interposed between the core and shell, said auxiliary front having portions fashioned to permit the passage of air therethrough and other portions completely concealing said headers. 30
11. The combination with a radiator unit comprising a core having upper and lower headers and tubes connecting said headers, of a front simulating a shutter unit for concealing said core, said front including upper and lower transversely extending webs arranged in advance of said upper and lower headers, and ribs arranged vertically of said front connecting said upper and lower webs and fixed against movement with respect thereto. 35
12. The combination with a radiator unit comprising a core having upper and lower headers and tubes connecting said headers, of a front simulating a shutter unit for concealing said core, said front including upper and lower transversely extending webs arranged in advance of said upper and lower headers for concealing the same, and ribs arranged vertically of said front, said ribs having end portions extended to overlie the said webs. 40
13. The combination with a radiator unit comprising a shell and a core positioned in the rear of the shell and having upper and lower headers normally visible through the opening in the shell, of an auxiliary front within the shell simulating a shutter unit and substantially concealing said core, said auxiliary front including upper and lower transversely extending webs of sufficient width to substantially conceal said upper and lower headers, and vertically arranged ribs, said ribs having extended end portions which overlie said webs. 45
14. The combination with a radiator unit comprising a core having upper and lower headers and tubes connecting said headers, of a front simulating a shutter unit for concealing said core, said front including a single piece of sheet metal having upper and lower web portions of sufficient width to substantially conceal said headers and having vertically arranged rib portions, said web portions being crimped to constitute extensions of said ribs. 50
- In testimony whereof I affix my signature. 105
